S. HARRISON

Des. 165,649

INFLATED TOY

Filed May 2, 1951

FIG. 1.

FIG. 2.

FIG. 3.

UNITED STATES PATENT OFFICE

165,649

INFLATED TOY

Seymour Harrison, Brooklyn, N. Y., assignor to
Plastics Innovations, Inc., New York, N. Y., a
corporation of New York

Application May 2, 1951, Serial No. 15,042

Term of patent 3½ years

(Cl. D34—15)

To all whom it may concern:

Be it known that I, Seymour Harrison, a citizen of the United States of America, residing at Brooklyn, county of Kings, and State of New York, have invented a new, original, and ornamental Design for an Inflated Toy, of which the following is a specification, reference being had to the accompanying drawing, forming part thereof.

In the drawing:

Fig. 1 is a top view of an inflated toy showing my new design;

Fig. 2 is an elevational view thereof; and

Fig. 3 is a sectional view taken on the line 3—3 of Fig. 1.

I claim:

The ornamental design for an inflated toy, substantially as shown.

SEYMOUR HARRISON.
